UNITED STATES PATENT OFFICE.

PETER H. STOSECH, OF CLIFFSIDE, NEW JERSEY.

COMBINATION-LOCK.

1,377,737.

Specification of Letters Patent.

Patented May 10, 1921.

Application filed March 26, 1920. Serial No. 369,145.

To all whom it may concern:

Be it known that I, PETER H. STOSECH, citizen of Russia, residing at Cliffside, county of Bergen, State of New Jersey, have 5 invented a new and useful Improvement in Combination-Locks, of which the following is a specification.

This invention relates to locks, and particularly to those adapted for use on a trunk, 10 bureau or similar article.

One of the objects is to provide a lock suitable for use on a trunk, bureau, cabinet, wall-safe, or similar article and one in which a bolt-lock is so combined with a movable 15 permutation device as to offer effective resistance against being picked or opened except by one who knows the combination of the permutation device, the proper manner of manipulating the same, and uses a particular key.

A further object is to provide a lock containing a plurality of interlocking bolt-locks and one which cannot be unlocked except by following, in a proper order, a 25 certain sequence of manipulation of the bolt-locks.

A further object is to provide a lock comprising a plurality of bolt-locks so combined with a permutation device that the 30 permutation device must first be set and properly manipulated before any of said bolt-locks may be opened,—and then the bolts must be operated in a certain sequence to open the lock itself.

Another object is to provide a lock of the above type which, after being locked with the key, holds the key against removal until the permutation device is set and manipulated in a certain manner.

Further objects include the provision of 40 a lock of the above type which comprises a minimum of parts; one which may be easily and inexpensively manufactured; and one which is simple to operate, and at the same time renders secure protection.

In the accompanying drawings wherein is shown one of the various possible embodiments of this invention—

Figure 1 is a front elevation of the lock; 50 Fig. 2 is the same as Fig. 1 with the cover plate removed, showing the lock in shut condition, and partly in section on the line 2—2 of Fig. 3;

Fig. 3 is a section on the line 3—3 of Fig. 2 with the cover plate in place;

55

Fig. 4 is a similar view to Fig. 2, except the lock is shown in open position;

Fig. 5 is a section on the line 5—5 of Fig. 4 with the cover plate in place; and

Fig. 6 is a section on line 6—6 of Fig. 4, 60 with the cover plate in place.

Similar reference characters refer to similar parts throughout the several views of the drawings.

It will be noticed that the drawings show 65 a lock comprising, in combination, three separate bolt-lock mechanisms, and a permutation device, all suitably contained in a box or casing having a base plate 1 and a cover plate 2. The lock mechanism shown 70 at the right in the drawings comprises a sliding bolt-bar 3 having bolt 4 and a stump 5 extending into superimposed slots 6 of two tumbler plates 7 and 8, respectively, each pivotally mounted on the base plate 1 at 9, 75 and respectively held, by means of springs 10 and 11 attached to the tumblers and to posts 12 and 13 carried on base 1 to prevent movement of the bolt from locked or unlocked position unless the tumblers 7 and 8 are raised to permit sliding of stump 5 in 80 slots 6. Bolt-bar 3 is provided with a perforation 14 adapted to receive a key 15 when inserted through key-hole 16 in the casing; the perforation being so shaped and 85 the tumblers 7 and 8 so cut and positioned relative to perforation 14 that proper movement of the key 15 will manipulate the tumblers 7 and 8 and effect locking or unlocking movement of the bolt 4, a step of key 15 being adapted to enter a recess 17 (shown in dotted lines) of said perforation 14 during 90 such movements. Perforation 14 is also shaped so that upon a reverse movement of the key in the proper direction the key will 95 contact with the bolt-bar 3 outside of the recess 17, and will thereby be prevented from actuating the tumblers 7 and 8 or bolt 4. A second lock mechanism comprises bolt-bar 18, pivoted to base 1 at 19, and comprises 100 a bolt portion 20. A third lock mechanism comprises bolt-bar 21 also pivoted to base 1 at 19, and comprises bolt portion 22. Bolt-bars 18 and 21 are mounted in opposite and superimposed relation, bolt-bar 21 being 105 above bolt-bar 18 and both are continually

urged into locked position by spring 23 mounted on base 1 as at 24. A space is provided between bolt-bars 18 and 21 to receive a dormant key 25 mounted on and projecting through the casing 2 and provided with knob 26, a one-quarter turn of which causes unlocking or locking movement of the bolts 20 and 22 simultaneously. Bolt-bar 18 and bolt-bar 3, however, when in locked position, 10 abut each other, as shown in Figs. 2 and 3, so that unlocking movement of bolt-bars 18 and 21 may not be had while bolt-bar 3 is in locked position.

A pair of concentric disks 27 and 28 are 15 normally positioned, abutting bolt-bar 21 when in locked position, as shown in Figs. 2 and 3, so as to prevent unlocking movement of bolts 20 and 22 until these disks have been moved out of the path of bolt-bar 20 21, as shown in Figs. 4, 5 and 6. Disks 27 and 28 form part of a permutation device and 25 are mounted on collars 29 and 30, respectively, extending through cover plate 2 (see Fig. 6) for independent rotation and for simultaneous movement toward and away 30 from base 1. Disks 27 and 28 contain a plurality of similar perforations 31 and 32, respectively, perforations 31 being adapted to be brought into register with perforations 32 by independent rotation of disks 27 and 28, and both sets of perforations adapted to be brought in register with similarly placed 35 studs 33 fixed on base 1, so that when the perforations of both disks and studs 33 are all in register, disks 27 and 28 may be moved downward over studs 33 and out of normal position and out of the path of movement of bolt-bar 21 to permit unlocking movement of bolt 22, but when perforations 31 and 32 40 are not in register with each other or with studs 33, the studs will arrest the movement of the disks out of normal position and prevent unlocking movement of bolt-bar 21 and bolts 20 and 22. A spiral spring 34 between 45 disk 27 and base 1 continually urges the permutation device into normal position.

A latch comprising latch bar 35, pivotally mounted on base 1 as at 36 and carrying a lug 37 is adapted to enter a recess 38 in bolt-bar 3 to prevent unlocking movement of bolt-bar 3, and into perforation 14 to contact with and prevent turning of the key 15 in unlocking direction to contact with the tumblers 7 and 8 or bolt-bar, as shown in 50 Fig. 2, or to prevent removal of the key 15 if positioned on the other side of lug 37. Lug 37 may be continually urged to enter recess 38 by upward pressure of spring 50 mounted on base 1 at 51 against the latch bar 35 at 52. Downward movement of disks 55 27 and 28 releases the latch to lift lug 37 out of recess 38 and permits unlocking movement of bolt-bar 3, the turning of key 15 to unlock or the removal of key 15 after shooting the bolt.

Collar 30 carries knob 39 and dial 40, to rotate with disk 28, and collar 29 carries knob 41 and dial 42 to rotate with disk 27. The dials 40 and 42 carry the usual marking or combination numbers and are independently rotatable in respect to a mark 43 on the cover plate 2 to indicate when the perforations of disks 27 and 28 and studs 33 are in register with each other and with studs 33, and show when the permutation 75 device is set.

Studs 33 may be mounted on a ring or plate 44 which may be removably screwed to base 1 as at 45, so that the plate and studs may be moved, thereby requiring a different 80 combination of numbers or dials 40 and 42 to come opposite mark 43 to indicate that the permutation device is set.

53 (Fig. 2) indicates portion of a trunk or other element desired to be held fast by 85 the lock, and carries a pair of hasps 46 and 47 adapted to project, respectively, through perforations 48 and 49 of the lock casing, hasp 46 being adapted to receive and be held by bolt 4, and hasp 47 being adapted to receive and be held by bolts 20 and 22.

In operation the permutation device is first set by turning knobs 39 and 41 and the dials 42 and 43 carried thereby until the proper numerals on the dials are opposite 95 mark 43 and indicate that the device is set. Then the device is pushed inwardly, bringing the disks 27 and 28 over studs 33 and out of the path of bolt-bar 21. This movement also lifts lug 37 to permit of the next operation, which comprises inserting and turning key 15 and thereby open lock 4, after which, and with the permutation device still pressed inward, locks 20 and 22 may be opened by turning knob 26.

A quarter turn of knob 26 will shoot locks 20 and 22, and by turning the key 15, lock 4 may be shot but this key may not then be removed unless the permutation device is set and moved inwardly to hold lug 37 out of 110 the path of the key.

It is to be understood that the terms "bolt-bar" and "bolt member" as used throughout this specification and in the appended claims refer only to such members which comprise 115 a hasp-engaging or keeper-engaging "bolt" as that word is usually employed in the lock art, and not to any other member which may have the general shape of a "bolt" when considered apart from this art.

Having thus described the invention, what is claimed is:

1. A device of the character described, comprising, in combination, three or more hasp or keeper engaging bolt members, and 125 movable means adapted, when in a predetermined position, to prevent unlocking movement of three of said bolt members.

2. A device of the character described, comprising, in combination, a plurality of 130

hasp or keeper engaging bolt members, movable means adapted, when in a predetermined position, to prevent unlocking movement of one of said bolt members, said 5 means comprising a permutation device adapted, when set, to be moved out of said predetermined position to permit unlocking movement of said bolt members.

3. A device of the character described, 10 comprising, in combination, a plurality of hasp or keeper engaging bolt members, movable means adapted, when in a predetermined position, to prevent unlocking movement of two of said bolt members, said 15 means comprising a permutation device adapted, when set, to be moved to permit unlocking movement of said two bolt members.

4. A device of the character described, 20 comprising, in combination, three or more hasp or keeper engaging bolt members, movable means adapted, when in a predetermined position, to prevent unlocking movement of two of said bolt members, said 25 means comprising a permutation device adapted, when set, to be moved to permit unlocking movement of said three bolt members, one of said lock mechanisms, when in locked position, being adapted to prevent 30 unlocking movement of a third of one of said bolt members.

5. A device of the character described, comprising, in combination, a pair of hasp or keeper engaging bolt members, a key 35 adapted to be moved to effect simultaneous actuation of said bolt members, and a third hasp or keeper engaging bolt member adapted, when in a predetermined position, to prevent actuation of one of said pair of 40 bolt members into open position.

6. A device of the character described, comprising, in combination, a pair of bolt members, a key adapted to be moved to effect simultaneous actuation of said bolt members, movable means adapted, when in a predetermined position, to prevent actuation of one of said members into open position, and movable means adapted, when in a predetermined position, to prevent actuation 50 of the other of said members into open position.

7. A device of the character described, comprising, in combination, a pair of bolt members, movable means comprising a lock mechanism adapted, when in locked position, to prevent movement of one of said bolt members into unlocked position, and movable means comprising a permutation device adapted, when in normal position, 55 to prevent movement of the other bolt member into unlocked position.

8. A device of the character described, comprising, in combination a pair of bolt members, movable means comprising a lock mechanism adapted, when in locked posi- 60

tion, to prevent movement of one of said bolt members into unlocked position, movable means comprising a permutation device adapted, when in normal position, to prevent movement of the other bolt member into unlocked position, actuating means for said lock mechanism, and means adapted to render said actuating means inoperative to effect unlocking movement of said lock mechanism. 70

9. A device of the character described, comprising, in combination, a pair of bolt members, movable means comprising a lock mechanism adapted, when in locked position, to prevent movement of one of said bolt members into unlocked position, movable means comprising a permutation device adapted, when in normal position, to prevent movement of the other bolt member into unlocked position, actuating means for said lock mechanism, and means adapted to render said actuating means inoperative to effect unlocking movement of said lock mechanism, and movable means comprising a permutation device being adapted, when set, 80 to be moved to render said lock mechanism responsive to said actuating means. 85

10. A device of the character described, comprising, in combination, a pair of bolt members, movable means comprising a lock mechanism adapted, when in locked position, to prevent movement of one of said bolt members into unlocked position, a key, adapted by its movement, to place said lock mechanism in unlocked position, spring 95 means adapted to engage said lock mechanism, when in locked position, to prevent said lock mechanism being placed in unlocked position by means of said key, movable means comprising a permutation device 100 adapted to prevent movement of the other of said bolt members into unlocked position and adapted when set, to be moved to permit movement of said second bolt member into unlocked position and to disengage 110 said spring means from said lock mechanism to permit actuation of said lock mechanism into unlocked position by said key. 105

11. A key lock comprising, in combination, a bolt, a bolt bar, a key adapted to be moved to actuate said bolt bar into locked or unlocked position, a movable member normally locking said bolt bar against movement and adapted to be engaged by said key to permit predetermined movement of 115 said bolt bar, spring means comprising a latch adapted to lock said bolt bar in locked position, and to prevent engagement of said movable member by said key and manually operative means whereby said latch may be 120 released to allow engagement of said movable member by said key to permit movement of said bolt bar from locked position. 125

12. A device of the character described, comprising, in combination, a movable bolt 130

bar comprising a bolt, a key adapted to engage said bolt bar to cause said bolt to move into locked or unlocked position, spring means comprising a latch adapted to engage said bolt bar and to prevent engagement of said bolt bar by said key, and means comprising a permutation device adapted, when set, to be moved to disengage said latch from said bolt bar and permit said bolt to be opened by means of said key. In testimony whereof I have signed this specification. 10

PETER H. STOSECH.
